(57) **CLAIM**

I claim the ornamental design for a door jamb hinge plate locator, as shown and described.

DESCRIPTION

FIG. 1 is a forward upper perspective view of a door jamb hinge plate locator;

FIG. 2 is a forward lower perspective view thereof;

FIG. 3 is a top view thereof;

FIG. 4 is a first side view thereof;

FIG. 5 is a second side view thereof;

FIG. 6 is a bottom view thereof;

FIG. 7 is a front view thereof; and,

FIG. 8 is a rear view thereof.

The broken lines illustrate portions of the door jamb hinge plate locator that form no part of the claimed design.

1 Claim, 4 Drawing Sheets
